UNITED STATES PATENT OFFICE.

CONRAD HAMMER, OF BUFFALO, NEW YORK.

TAPPING DEVICE.

SPECIFICATION forming part of Letters Patent No. 670,229, dated March 19, 1901.

Application filed July 21, 1900. Serial No. 24,418. (No model.)

To all whom it may concern:

Be it known that I, CONRAD HAMMER, a citizen of the United States, residing at Buffalo, in the county of Erie and State of New York, 5 have invented certain new and useful Improvements in Tapping Devices, of which the following is a specification.

My invention relates to an improved tapping device principally adapted for barrels or 10 kegs containing beer, ale, or other beverages; and the main object of the invention is to arrange the vent-tube upon a separate part, which will not rotate to wind the rubber or other tubing attached to the vent around the 15 device, and thus necessitate the detachment of the tubing when the tapping device is screwed into a keg or barrel.

It also relates to certain details of construction, all of which will be fully and clearly 20 hereinafter described and claimed, reference being had to the accompanying drawings, in which—

Figure 1 is a side elevation of my improved tapping device. Fig. 2 is a central longitudinal section on line *a a*, Fig. 3. Fig. 3 is a top plan view. Fig. 4 is a vertical central longitudinal section through the vent-tube. Fig. 5 is a detached top plan view of the rubber valve part. Fig. 6 is a section on line *b b*, 30 Fig. 5.

In referring to the drawings for the details of construction like numerals designate like parts.

A bushing 1, of any suitable metal, is screwed 35 into an opening in a suitable portion of a keg or barrel. This bushing is provided with a top flange or shoulder 2 and a central opening, the upper portion 3 of which is screw-threaded and extends from the top downward 40 to about midway the bushing and merges in an intermediate smooth-surfaced portion 4, which in turn enlarges into an annular groove 5. The groove has a horizontal top wall extending at substantially a right angle to the 45 intermediate opening and a diagonal downwardly and inwardly extending lower wall, which terminates in the bottom portion 6 of the central opening. The bottom portion 6 is formed slightly larger in circumference than 50 the intermediate portion 4, so that the top wall of the groove will form a shoulder or

stop for a cork or bung, seated in the bottom portion to prevent its withdrawal outwardly.

The tapping device consists of an upper member or part 7, a lower member or part 8, 55 and a vent-supporting member or part 9, which is fitted upon a reduced portion of the lower member or part. The upper member 7 has a central opening 10, an exterior screw-threaded portion 11, and a pair of turning handles 12. The lower member 8 has an enlarged upper screw-threaded opening 13, into which the screw-threaded portion 11 of the upper member is screwed, a reduced portion 14, having a reduced central opening 15, and a 60 screw-threaded end 16, which screws into the screw-threaded portion 3 of the bushing, and one or more transverse openings 17. The vent-supporting member 9 is tubular in form and has a transversely-extending interiorly- 65 screw-threaded tubular portion 18, into which the vent-tube 19 screws. The vent-tube is provided with a serrated outer end 20, to receive the end of rubber or other tubing, and an annular groove 21 near its inner end, into 70 which the inwardly-extending flange 22 of a flexible rubber valve part 23 is detachably sprung. This rubber valve part 23 is formed substantially as shown in Figs. 5 and 6, having a flat extension 24, provided with an elongated 75 opening 25 and a valve-chamber 26, and is fitted upon the inner end of the vent-tube, so as to act as a one-way valve. The opening in the vent-supporting member is sufficiently 80 larger than the reduced portion of the lower member to leave an air-conducting space 28 between the exterior of the lower member and the interior of the vent-supporting member. The vent-supporting member is also provided with an annular groove 29, which registers 85 with the vent-valve 23 and forms an enlarged air-conducting chamber. The air-conducting space 28 extends nearly the entire length of the vent-supporting member and is closed at the top and bottom by the opposed flanges 30 90 and 31, which extend, respectively, from the lower member and the vent-supporting member. (See Fig. 2.) Rubber or leather gaskets 32 and 33 are interposed between the top edge of the vent-supporting member and the shoulder 34 of the enlarged upper portion of the lower member and the top flange of the bush- 95 100

ing and the lower edge of the vent-supporting member. A hollow circular ring 35, of rubber or other suitable material, is interposed between the lower edge of the upper member and the bottom wall of the enlarged screw-threaded opening in the lower member. The lower member is also provided with a pair of lateral projections or turning handles 36. The upper member has an inwardly-extending flange 14^a at its lower end, which is provided with a reduced central opening 15^a and forms an annular compressing-shoulder for the hollow circular ring 35. (See Fig. 2.)

The operation of the device is as follows: 15 The bushing 1 being properly screwed into an opening in a keg or barrel, the lower end of the lower member of the tapping device is screwed into the opening in the bushing. The vent-supporting member remains stationary 20 while the lower member is rotated nearly into place, thereby preventing the winding of the hose or flexible tubing connected to the vent-tube around the tapping device. The tap is now inserted in the opening in the tapping 25 device, the upper member is screwed downward sufficiently to contract the ring 35 around the tap, and the tap is driven in, forcing the cork or bung into the keg or barrel.

I claim as my invention—

30 1. A tapping device comprising a lower member adapted to screw into a keg or barrel, an upper member screwing into the upper end of the lower member and a vent-supporting member loosely mounted on the lower 35 member, and adapted to remain stationary when the lower member is screwed into the keg or barrel, and to be tightly secured in

place when the tapping device is screwed firmly in the keg or barrel.

2. A tapping device comprising a tubular lower member having a screw-threaded lower end adapted to screw into a keg or barrel, an enlarged internally-screw-threaded upper end and an intermediate reduced portion, a tubular upper member screwing in the interior screw-threaded upper end of the lower member, and a tubular vent-supporting member of slightly-larger interior circumference than the intermediate reduced portion and fitted upon said reduced portion, substantially as set forth.

3. A tapping device comprising a tubular main member adapted to screw into a keg or barrel, and having an enlarged upper portion and a reduced portion and a tubular vent-supporting member of slightly-larger circumference than the reduced portion fitted upon said reduced portion.

4. A tapping device comprising a tubular main member adapted to screw into a keg or barrel, and having an enlarged upper portion and a reduced portion, a tubular vent-supporting member of slightly-larger circumference than the reduced portion fitted upon said reduced portion, and packing-rings between the upper end of the vent-supporting member and the enlarged upper portion of the main member and the lower end of the vent-supporting member and the keg or barrel, substantially as set forth.

CONRAD HAMMER.
